GAS-BURNER STRUCTURE

Application filed February 16, 1929. Serial No. 340,459.

This invention relates to a gas burner having an orifice for the control of gas so located and shielded as to prevent tampering therewith. The present invention relates to a Bunsen type of burner such as may be used for heating various devices among which may be mentioned water heaters. Commonly, such devices have a burner tube with air inlets for primary air, an orifice for passage of the gaseous fuel and a burner tip or head. The orifice is commonly designed and initially constructed for the correct amount of gas for an efficient air-gas ratio. If the orifice is increased in cross sectional area, the volume of gas passing per unit of time therethrough is increased so that incomplete combustion may occur with consequent dangers of asphyxiation. Such orifices, if accessible to boring tools from the outside, are often increased in size by the users due to their misunderstanding of combustion and design.

The objects of this invention are to provide a burner having any or all of the following features: An integral base and burner tube with an orifice plug in position with the burner so as to be inaccessible to tools from without; means provided to insert the orifice plug during manufacture and to permanently seal the place of insertion making the entire burner substantially integral; and certain features contributing to strength, simplicity and economy of structure.

These objects together with other objects and corresponding accomplishments are obtained by means of the embodiment of my invention illustrated in the accompanying drawing, in which:—

Fig. 1 is an elevation of a twin burner embodying my invention; Fig. 2 is a plan view as seen on the line 2—2 of Fig. 1; and Fig. 3 is a section through one of the burner tubes.

Referring more particularly to the drawing, 5 indicates a manifold serving as a base for burner tubes 6^a and 6^b formed integral therewith. An inlet 7 for gas is provided in the manifold. The burner tubes and base may be made of cast iron. At the juncture of the passage in the base 5 and the bore of the burner tubes are openings or bores 8 to receive orifice plugs. Each burner tube has

air ports 9 for the admission of primary air and lateral slits 10 forming flame or jet openings. The upper ends of the burner tubes are initially constructed with openings in alignment with the orifice openings 8 and finally are sealed with closure plugs 11 which are preferably forced into the openings so as to provide a pressed fit. The orifice plugs 12 are preferably made of brass or like material and are hollow having bores 13 ending with orifices 14 which are made of proper size to provide the most efficient air-gas ratio.

The burner tubes and base are preferably integral, the openings 8 being machined and the orifice plugs inserted in position through the openings in the heads of the burner tubes. After the insertion of the orifice plugs, the tubes are sealed by pressing into position the closure plugs 11. Thus, the plugs are undetachable and access cannot be had to the orifices 14 from the ends of the tubes. The air ports 9 are such that the orifices can only be reached at an angle. It is obvious, that the closure plugs may be fixed in position by any other suitable mechanical expedients making them undetachable.

What I claim is:

1. A burner comprising a base having an inlet passage, a burner tube outstanding from said base and integral therewith, an orifice at the juncture of the bore of said tube and the passage in said base, an undetachable head closing the outer end of the bore of said tube, said head having an opening in alignment with the bore of said tube to enable access to said orifice during manufacture and a closure plug permanently fixed in position and sealing said opening.

2. A burner comprising a base having an inlet passage, a burner tube outstanding from said base and integral therewith, an aperture at the juncture of the bore of said tube and the inlet passage of said base, said tube having an undetachable head closing the outer end of its bore, and an orifice plug fixed in said aperture, said head having an opening in alignment with the bore of said tube to enable access to said orifice plug opening during manufacture, and a closure plug

permanently fixed in said opening and sealing said head.

3. A burner comprising a base having an inlet passage, a burner tube outstanding from said base and integral therewith, an orifice at the juncture of the bore of said tube and said base, said tube having an undetachable head closing the outer end of its bore, said head having a pressed fit closure plug in alinement with the bore of said tube to enable access to said orifice during manufacture.

4. A burner comprising a base having an inlet passage, a burner tube outstanding from said base and integral therewith, an aperture at the juncture of the bore of said tube and the inlet passage of said base, said tube having an undetachable head closing the outer end of its bore and an orifice plug fixed in said aperture, said head having a pressed fit closure plug in alinement with the bore of said tube to enable said orifice plug to be positioned in said aperture during manufacture.

5. A burner comprising a base having an inlet passage, a straight burner tube outstanding therefrom and integral therewith having a burner head provided with lateral flame slits, an aperture at the juncture of the bore of said tube and the inlet passage in said base, said tube having an undetachable head closing the upper end of its bore, said head having a pressed fit closure plug in alinement with the bore of said tube to enable access to said aperture during manufacture, and an orifice plug in said aperture.

6. A burner comprising a base having an inlet passage, a straight burner tube outstanding therefrom and integral therewith having a burner head with its upper end wall closing the bore of said tube and lateral flame slits, an orifice at the juncture of the bore of said tube and the passage in said base, said head having an opening in its end in alinement with the bore of said tube to enable access to said orifice during manufacture and a closure permanently fixed in position in said opening.

7. A burner comprising a base having an inlet passage, a straight burner tube outstanding therefrom and integral therewith having a burner head with lateral flame slits, an aperture at the juncture of the bore of said tube and the inlet passage in said base, said tube having an undetachable head closing the outer end of its bore, an orifice plug fixed in said aperture, said head having an opening in alinement with the bore of said tube to enable said orifice plug to be positioned in said aperture, and a closure plug permanently fixed in said opening and sealing the latter.

8. A burner comprising a base having an inlet passage, a straight burner tube outstanding therefrom and integral therewith

having a burner head provided with an end wall closing the bore of said tube and lateral flame slits, an orifice at the juncture of the bore of said tube and the passage through said base, said head having a pressed fit closure plug in alinement with the bore of said tube to enable access to said orifice during manufacture.

9. A burner comprising a base having an inlet passage, a straight burner tube outstanding therefrom and integral therewith having a burner head with lateral flame slits, an aperture at the juncture of the bore of said tube and the inlet passage in said base, said tube having an undetachable head closing the outer end of its bore, an orifice plug fixed in said aperture, said head having a pressed fit closure plug in alinement with the bore of said tube to enable said orifice plug to be positioned in said aperture.

In witness that I claim the foregoing I have hereunto subscribed my name this 25th day of January, 1929.

JOHN H. GRAYSON.
